UNITED STATES PATENT OFFICE

WILLIAM JOHN NORTON, OF SALFORD, MANCHESTER, ENGLAND, ASSIGNOR TO SIR JAMES FARMER NORTON & COMPANY LIMITED, OF MANCHESTER, ENGLAND, A BRITISH COMPANY

DYE JIGGER

Application filed July 20, 1931, Serial No. 552,059, and in Great Britain March 27, 1931.

This invention relates to dye jiggers, and has for its object to provide a simple and reliable arrangement of the driving means for the driven rollers of the jigger whereby

5 I am enabled to obtain a practically uniform cloth speed between the rollers notwithstanding their relative diameters due to the amount of cloth thereon at any moment. A further object of the invention is to provide 10 an improved arrangement of reversing mechanism which does not necessitate the employment of spring or like loaded devices within the cloth folds on the rollers, which devices are exposed to the dye liquor and may 15 mark the fabric.

The invention comprises the improved combinations and arrangements of parts hereinafter described and claimed.

20 Referring to the four accompanying sheets of explanatory drawings:—

Figure 1 is an end view, Figure 2 a front view and Figure 3 a rear view of a dye jigger having my improved drive applied thereto.

25 Figures 4 and 5 are detail views of the brake to be hereinafter described.

Figure 6 is a diagrammatic view of the electric control panel and

30 Figure 7 is a detail view of the means for determining the automatic stopping of the machine, this view being taken at right angles to the view of the similar parts in Figure 6.

The same reference letters in the different views indicate the same or similar parts.

35 The dye jigger illustrated comprises the two driven rollers *a*, *b* and the guide rollers *c*, *d*, *e* within the dye vat *f*. The rollers *c*, *d*, *e* are turned by the cloth as it travels between the driven rollers *a* and *b*.

40 The rollers *a*, *b* are each driven by a separate direct current electric motor *g*, *h* through spur gearing *i*, *j*.

Upon the shaft of the roller *b* is mounted a worm *k* which drives a worm wheel *m* on a shaft *n* which by means of a worm *o* and worm wheel *p* drives a disc *q* upon the peripheral edge of which dogs *r*, *s* are clamped so that they can operate an arm *t* to be hereinafter referred to.

45 The shaft of each of the rollers *a*, *b* carries a one-way clutch, as shown in Figures 4 and

5, for causing the rotation of a brake drum *u* with which engages a brake band *v* anchored at *w* to the bracket *x* supporting a bearing of the roller shaft. The brake pressure is adjusted by the hand wheel *y*. When the roller *a* or *b* is travelling in the direction which pays out or delivers cloth therefrom, the rollers *z* of the one way clutch cause the drum *u* to rotate with the roller shaft so that the brake band *v* exerts a definite resistance to the rotation of the shaft, and thus any overrunning of the fabric is prevented. 55

When the roller *a* or *b* is rotating in a direction to wind cloth thereon, the one-way clutch is inoperative as the rollers *z* move 60 clear of the drum *u*; the brake has, therefore, no effect upon the rotation of the roller by its motor.

65 The armatures of the two motors *a* and *b* are arranged in series in the supply main, as shown in Figure 6 where the armatures are indicated at 8 and 9.

70 The field windings of the motors indicated at 10 and 11 are in parallel between the supply mains. 75

75 The connections to the commutator brushes of the armatures are made to two pairs of terminals 12, 13 and 14, 15, and these terminals are connected to two solenoid or electro-magnetically operated switches 16 and 17, the connections to 17 being open connections and the connections to 16 being crossed connections, so that if 16 be closed the current will flow in one direction through the armatures and if 17 be closed it will flow in the reverse 80 direction. 85

The electric mains are indicated by 18 and 19.

90 The switches 16 and 17 are controlled by electro-magnetic coils 20 and 21 connected by the lead 22 through the lamp 23 which acts as a resistance to the main 18 and by the two leads 24 and 25 with contacts 26, 27 with which can engage a contact blade 28 connected to a lead 29 which is connected by contact 95 blades 30, 31 with the main 19.

95 The contact blade 28 would normally engage the contact 26 but it is controlled by a cam like part 32 upon the fulcrum of an arm 33 having a pointed upper end adapted to be 100

engaged by the pointed lower end of a plunger 34 within an arm 35 which turns with the arm *t*. A spring 36 presses the plunger 34 towards the arm 33. Stops 37, 38 limit the movements of the arms 33 and 35. In Figure 6, the arms 33 and 35 are drawn in a mid or neutral position for the sake of clearness but it will be understood that they never occupy such position in practice for the arrangement provides in a known manner for a snap or quick action of the arms 33 and 35 from one stop to the other as the arm *t* is moved by the dogs *r*, *s* upon the disc *q*.

The contacts 30 and 31 are normally in engagement but they can be moved apart by a cam 40 upon a spindle 41 upon which two ratchet wheels 42, 43 are secured and about which two pawls carrying arms 44 and 45 fulcrum. One arm 44 is connected by a link 46 to the arm *t* and the other arm 45 is connected by a link 47 to the arm 35. The pawls are numbered 48 and 49 respectively. This arrangement of two ratchet wheels and two pawls operated from the opposite sides of the fulcrum point of the arm *t* ensures that the shaft 41 is turned through a distance represented by a tooth of the ratchet wheels each time *t* is moved, whether to the right or to the left. After the ratchet wheels have been turned through a certain number of teeth dependent upon the initial relationship of the cam 40 to the blade 30, the latter is moved clear of 31 and the circuit through the blade 38 and the coils 20, 21, broken. The pointer or finger 50 (Figure 2) indicates the position of the cam 40 and allows the operator to set the same to determine the number of times the cloth is passed from *a* to *b* and back from *b* to *a* before the machine is stopped automatically.

With the improvement in which two direct current motors *g*, *h* having their armatures arranged in series drive the driven rollers *a*, *b* of the machine, as one roller increases in diameter and becomes heavier due to the winding of cloth thereon, the motor driving the same tends to slow down, whilst the motor driving the other roller which is becoming lighter as the cloth is removed therefrom, tends to speed up. There is thus an automatic balancing action between the motors which gives the desired uniformity of cloth speed under all conditions of winding on to and unwinding from rollers, with a uniform cloth tension between the rollers. The simplicity of the arrangement is at once apparent as it does not depend upon any mechanical action resulting from changes in diameter of the rollers on to and from which winding is taking place.

The reversing mechanism depends for its actuation upon the position of the dogs *r*, *s* upon the disc *q*. If *s* strikes *t* (Figure 2), the latter is moved to the left and causes through the plunger 34, the arm 33 to be

moved to the right so depressing the blade 28 and making contact between 28 and 27. The coil 21 is thus energized and the armature circuit closed through the open connections at 12 and 13.

The cam 40 is turned through an angular distance equal to one pawl of the ratchet wheels 42 and 43. The next time the arm *t* is engaged, it is by the dog *r* which moves *t* to the right. The arm 33 is also moved to the left and the coil 20 energized. The armature circuit is then closed through the crossed connection at 14, 15.

It will be noted that no part of the driving and reversing mechanism is within the dye vat *f* so that fouling of parts by the dye liquor or striping of the fabric by parts engaging the same are obviated.

The term "dye jigger" is used in this specification and in the appended claims with the meaning attached to it in the trade, namely, a machine for treating fabrics with liquor in which the cloth is paid out from one roller and received by another roller above the liquor, the latter serving for dyeing, washing, bleaching, scouring or other treatment of the fabric.

What I claim is:—

1. In dye jiggers, in combination, two driven rollers on to and from which the fabric being dyed is wound so that it passes through the dye liquor in the jigger, two direct current electric motors driving said driven rollers, the armatures of the motors being arranged in series in an electric circuit whereby an automatic speed balancing action according to weight of roller, is obtained.

2. In dye jiggers, in combination, a driven roller, a direct current electric motor driving said roller, a second driven roller, a direct current electric motor driving said second roller, fabric passing between said driven rollers and through the liquor in the dye jigger, a series electric connection between the two motor armatures, and means for reversing the direction of current in said series connection to reverse the direction of rotation of the rollers whilst maintaining a speed balancing action between the motors due to the mutual variation in weights of the rollers.

3. In dye jiggers, in combination, a driven roller, a direct current electric motor driving said roller, a second driven roller, a direct current electric motor driving said second roller, fabric passing from one driven roller to the other through the dye liquor in the dye jigger, a series electric connection between the armatures of the two motors, and means driven by one of said rollers for actuating switches to reverse the flow of current in said armatures.

4. In dye jiggers as claimed in claim 3, means actuated in unison with the reversing means for controlling the number of times

the motors are reversed before they are automatically stopped.

5. In combination, two driven rollers on to and from which a material is wound, two direct current electric motors driving said driven rollers, the armatures of the motors being arranged in series in an electric circuit whereby an automatic speed balancing action according to weight of

10 roller is obtained.

6. In combination, a driven roller having a material windable thereabout a direct current electric motor driving said roller, a second driven roller on to and from which the material on the first roller is wound, a direct current electric motor driving said second roller, a series electric connection between the two motor armatures, and means for reversing the direction of current in said series

15 connection to reverse the direction of rotation of the rollers whilst maintaining a speed balancing action between the motors due to the mutual variation in weights of the rollers.

20 25 In testimony whereof I have signed my name to this specification.

WILLIAM JOHN NORTON.
